LOUD-SPEAKER AND CIRCUIT THEREFOR

John J. Moynihan, Boston, Mass., assignor of
one-half to Joseph B. Brennan, Euclid, Ohio

Application February 17, 1942, Serial No. 431,258

11 Claims. (Cl. 179—1)

This invention relates to loud speakers and circuits therefor, and more particularly to the type of loud speaker used in conjunction with ordinary radio receivers or public address amplifiers wherein the energy for the operation of the speakers is derived from vacuum tube amplifiers and the like.

According to the usual practice in the art, such loud speakers ordinarily include a diaphragm, usually in the form of a cone, for emitting the sound, the diaphragm having attached to it a voice coil which ordinarily consists of a number of turns of fine wire and which carries a voice current corresponding to the sound to be reproduced. The voice coil is located in a magnetic field, the coil ordinarily being positioned in an air gap in an iron core. An exciting coil may be employed to provide a strong field at the region in which the voice coil is located. The alternating current flowing in the voice coil causes the voice coil to vibrate in the magnetic field, and these vibrations are transferred into sound by the diaphragm.

In ordinary radio receivers and public address amplifiers the output of the last vacuum tube includes not only the alternating voice current but a direct current component. Because of this fact it is the general practice to connect the output circuit to the primary of a transformer and the voice coil to the secondary of this transformer. This eliminates the direct current component of the plate current from the voice coil of the speaker and makes it possible more effectively to match the impedance of the plate circuit of the output tube with the impedance of the voice coil of the speaker. The system has several disadvantages among which may be listed the following: the magnetic circuit of the output transformer is biased by the presence of direct current in the primary winding, and if this primary current is sufficiently large, core saturation and, consequently, distortion of the wave form of the voice currents will take place in the output transformer; the leads from the voice coil of the speaker to the output transformer constitute a friction load on the diaphragm, the effect of which is variable from speaker to speaker of the same type and may be variable from time to time in any individual speaker as the leads occupy different positions; the field of the speaker is supplied with D. C. excitation which constitutes a power load on the rectifier-filter circuit of the receiver.

It is accordingly a general object of the present invention to provide a loud speaker and a

circuit therefor wherein the above mentioned difficulties are eliminated. Another object is to provide a loud speaker and circuit therefor wherein the necessity of employing a separate output transformer is done away with. A further object is to provide a simple loud speaker which requires no leads for the voice coil and which can be manufactured at low cost. Another object is to provide a loud speaker which is free from the friction load on the diaphragm ordinarily imposed by the voice coil leads. Another object is to provide an arrangement whereby the loud speaker field coil can act as a filter choke for the power supply or rectifier system of the receiver or amplifier. A further object is to provide a circuit and the loud speaker for use therein wherein the loud speaker is provided with field coils which may be used as impedances in an impedance-coupled amplifier. Another object is to provide loud speakers or sound transducers in which the response characteristics can be readily varied to suit particular requirements.

Further objects and advantages of my invention become apparent from the following description of various preferred forms thereof, reference being made to the accompanying drawings in which Figure 1 diagrammatically illustrates a loud speaker made according to my invention, in conjunction with a typical amplifier circuit modified in accordance with my invention; Figures 2, 3, 4, 5 and 6 diagrammatically illustrate modified forms of loud speakers suitable for use in circuits such as the circuit of Figure 1; Figure 7 diagrammatically illustrates an impedance-coupled amplifier embodying a loud speaker and a circuit of the present invention.

Briefly, according to my invention, I eliminate the need for a separately excited voice coil by inducing the voice currents in a short circuited voice coil or other conductor, which does not have any leads connected thereto. With such an arrangement, the output of the amplifier or receiver, instead of being connected to the speaker through an output transformer is connected directly to the field coil of the loud speaker. The direct current component of the output plate current furnishes the strong electromagnetic field for the speaker while the voice current component results in the inducing of a similar voice current in a conductor carried by the diaphragm and positioned in the field. The voice current so induced causes the conductor to vibrate in the magnetic field produced by the di-

rect current component of the output current. This vibration is transmitted to the speaker diaphragm, resulting in the production of sound.

In Figure 1 of the drawings, I have illustrated my invention as applied to a typical radio receiver. In the drawings I have omitted the units of the receiver in advance of the audio frequency amplifier and output stages, which may be conventional. The portion of the circuit illustrated includes the rectifier and filter units indicated generally at 10; the volume control network 11; the audio frequency amplifier stage 12; the output stage 14; the tone control network 15; and the loud speaker 16. The wiring diagram illustrated is conventional except for specific features which will be described in detail below. The values of the various resistances, inductances and capacitances may readily be determined by those skilled in the radio art.

It will be noted that the conventional output transformer is absent from this diagram. Instead, the plate current of the output tube 17 is conducted directly to the coil 18 of the loud speaker 16. This coil is wound upon a core 19, preferably laminated in order to reduce the effect of eddy currents, and having an air gap 20 in which the voice coil 21 is positioned. The voice coil 21, which may consist of a single turn, is mounted upon an extension 22 connected to the conical diaphragm 23. The diaphragm may be supported in conventional manner by flexible spiders or supports 24 and 25 mounted in a suitable framework (not shown).

As noted above, the plate current of the output tube 17 consists of two components, one a direct current component the value of which is determined by the design of the output tube and the voltage applied to its plate, and the other an alternating current signal or voice current which is a function of the signal or sound being reproduced. The direct current component of the output flowing through the coil 18 excites the core or field structure 19, producing a magnetic field or flux in the air gap 20. The alternating current component or voice current causes a voice current to be induced in coil 21 proportional to the voice current flowing through the coil 18. In this respect coil 21 may be considered as the secondary of a transformer of which coil 18 is the primary. As coil 21 is located in the air gap 20 where the magnetic flux is relatively large, the induced currents flowing in coil 21 cause it to move at any given instant in a direction and with a force determined by the instantaneous direction and value of the current flowing in the coil 21. Thus, the motion of coil 21 corresponds to the voice current component of the plate circuit of the output tube 17, and this motion is transmitted to diaphragm 23 and radiated into the air as sound as in an ordinary speaker.

In some instances and with some circuits the direct current component of the plate circuit of the output tube may be insufficient to provide the desired magnetic flux in the gap 20. When such a condition exists, an additional coil 26 may be wound on the field structure 19. This coil may be either connected across the direct current power supply or, as shown in the drawing, in series in the filter circuit where it acts as a choke, just as in conventional arrangements the speaker field may be used as a filter choke.

In Figure 2 I have illustrated a modified arrangement of a loud speaker adapted to be included in a circuit such as that shown in Figure 1. In this modification the field structure 19a

is provided with additional magnetic material at 28 immediately adjacent the air gap 20a, the purpose of the additional material being to increase the strength of the A. C. flux threading the coil 21a. This arrangement necessitates a slight modification in the supporting structure of the voice coil, the voice coil being connected to the diaphragm by spaced struts or legs 29 disposed on either side of the pole piece of the core 19a. Except for these changes the structure shown may be identical with that described with reference to Figure 1.

In Figure 3 another modified form of speaker is shown. Here the field structure 19b may be identical with that described with reference to Figure 1, but the voice coil 21b is a short-circuited multi-turn coil instead of the single turn shown in Figure 1. The coil may be designed with reference to the output of the amplifier and the field coil to provide the optimum number of ampere-turns. Also with this type of coil different response characteristics can be obtained. For example, if the coil is wound with wire composed of a material having a high temperature coefficient of resistivity, such as iron, the resistance of the coil will increase as it is heated by currents induced therein. Thus an increase in input to such a device does not result in an as great an increase in output, because of the effect of the increased resistance. Such a coil thus acts to contract the range of value of current flowing in the coil and of volume of sound reproduced.

The response characteristics can also be varied in other ways. For example, an impedance may be provided in the voice coil circuit, the impedance preferably being carried by the diaphragm or voice coil support. Thus if the coil current has a relatively large inductance, the response of the speaker to the higher frequencies will be lessened while the response to lower frequencies will be affected to a smaller extent, if at all. Likewise, if the coil is provided with a capacitance in series therewith, the response to the lower frequencies will be lessened, while the response to the higher frequencies will be affected to a smaller extent, if at all. A speaker having these characteristics is diagrammatically illustrated in Figure 4, where the coil 21c is connected in series with a condenser 30, the condenser also being supported for movement with the diaphragm 23c so as to avoid the necessity for any leads from the voice coil to a stationary part.

My principle of utilizing induced voice currents makes possible the use of the novel type of speaker shown in Figure 5 in which the field structure 31 is in the form of a U, one leg of which is wound with a coil 32 corresponding in general to the coil 18 of Figure 1 and to which the output current of the output tube of the amplifier may be supplied. Here, however, instead of using one or more turns as the voice coil, the flat plate 33 is employed. The flat plate being in the magnetic field created by the direct current 34 and the alternating current signal components of the output current will have eddy currents induced in it in the directions shown by the arrows, corresponding to the signal currents supplied to the coil 32. The field in the neighborhood of the pole 34 is distorted by means of a shading coil 35, thus producing a non-symmetrical field in the path of the induced eddy currents in the plate. The eddy currents act in the non-symmetrical field to reciprocate the plate 33 in directions parallel to its longitudinal axis and

with the reciprocations or vibrations proportional to the signal current supplied to the coil 32. The vibrations of the plate may be transformed into sound by connecting the plate to any convenient diaphragm, for example, the connection may be made directly to the apex of the conical diaphragm 36 which is supported in any suitable frame-work by supporting spiders 37 and 38.

In order to create the non-symmetrical relationship necessary for the motion of the plate, the arrangement shown in Figure 6 may be alternately used. In this arrangement a hole 39 is cut in the plate 33a so that the currents induced in the plate in the neighborhood of the pole 34a will be at any given instant preponderantly in the same direction.

My speakers, in which both alternating and direct current components are applied to the speaker field may be used effectively with amplifiers of types different from that shown in Figure 1. Thus, for some purposes impedance-coupled amplifiers are advantageous in that lower plate voltages and higher plate currents can be used in the various amplifying stages. However, heretofore the cost of such amplifiers has been considered practically prohibitive and they have not come into any extensive use. By my invention impedance-coupled amplifiers can be constructed at low cost by utilizing coils wound on the field structure of the loud speaker as the impedances. Such an arrangement is shown in Figure 7 in conjunction with a three stage, impedance-coupled amplifier, embodying a conventional circuit except for the features noted below. The arrangement of the diaphragm and voice coil is substantially identical with that described in conjunction with Figure 1, the same reference characters being applied to corresponding parts, but the field structure 40 not only has a coil 41 carrying the output current of the output tube 42, but also is provided with coils 43 and 44 wound on the outer legs of the field structure 40 and constituting impedances in the impedance couplings between tubes 45 and 46, and 46 and 42, respectively, and being connected in the plate voltage supply for the respective tubes. In this arrangement the coils are wound and connected as indicated diagrammatically in the drawing so that the direct current components of the currents flowing into the coils 43 and 44 aid in the production of the desired magnetic field in which the voice coil 21d operates. The connections are also such that the impedances of coils 32 and 33 to alternating voice currents are not neutralized by the interaction of the coils on the common core. This type of arrangement is advantageous in that a relatively high impedance can be provided in the plate circuit of each amplifier stage while the direct current resistance in the amplifier stages is relatively low. Thus it is possible to impress a higher percentage of the direct current power supply on the plate circuit of each tube, and this direct current may also be utilized to assist in energizing the speaker field.

From the foregoing description of various forms of my invention it will be evident that I have provided a loud speaker and circuit therefor whereby a speaker of the electro-dynamic type may be employed without any leads for moving conductor for the voice currents, with the result that the structure is simplified and the cost is reduced. As the friction load on the speaker occasioned by the leads to the voice coil is eliminated, the efficiency and response

characteristics of the speaker may be improved. The response characteristics may be varied to produce the desired effects. Further, by employing circuits according to my invention the output transformer ordinarily employed in amplifiers may be eliminated, the field structure and coil of the speaker serving the function of the output transformer. Also, with my invention the field structure may be wound with an additional coil constituting a filter choke and if desired my speakers may be employed in impedance-coupled amplifiers using coils wound on the field structures of the speakers as the impedances for the coupling. In all of these arrangements there is a net saving in the power required to operate the amplifier, for the direct current component of the output tube, which is ordinarily wasted as heat, is employed to create the field in which the voice coil operates. A further important saving is made in the elimination of the output transformer and in conjunction with the impedance-coupled amplifiers, the very material saving in eliminating the separate impedances ordinarily employed in amplifiers of this type.

Those skilled in the art will appreciate that various changes and modifications may be made in my invention without departing from the spirit and scope thereof. For example, features described with respect to one modification of my invention may be employed with other modifications, even though the specific arrangements are not described herein. It is therefore to be understood that my invention is not limited to the preferred forms described herein or in any manner other than by the scope of the appended claims.

I claim:

1. A loud speaker including in combination a ferro-magnetic field structure having an air gap, an exciting coil for magnetizing said field structure, and a short-circuited cylindrical voice coil situated in said air gap, said exciting coil being energized by a current having an alternating component superimposed on a direct component, said voice coil having an alternating current induced therein functional of the alternating component of the exciting current, and said voice coil being mounted so as to vibrate in said air gap due to the interaction of the flux in said air gap and the current in said voice coil.

2. A loud speaker including in combination a ferro-magnetic field structure having an air gap, an exciting coil for magnetizing said field structure, and a short circuited voice coil situated in said air gap, said exciting coil being energized by a current having an alternating component superimposed on a direct component, said voice coil having an alternating current induced therein functional of the alternating component of the exciting current, said voice coil being mounted so as to vibrate in said air gap due to the interaction of the direct current flux in said

air gap and the current in said voice coil, and means for increasing the alternating current flux threading said voice coil comprising ferromagnetic material in said field structure extending in parallel to said air gap adjacent said voice coil.

3. A loud speaker including in combination a ferro-magnetic field structure having an air gap, an exciting coil for magnetizing said field structure, a sound reproducing diaphragm, a short circuited voice coil supported by said diaphragm

and situated in said air gap, said voice coil having an impedance in series therewith, said impedance also being supported by said diaphragm, said exciting coil being energized by a current having an alternating component superimposed on a direct component, said voice coil having an alternating current induced therein functional of the alternating component of the exciting current, and said voice coil being mounted so as to vibrate in said air gap due to the interaction of the flux in said air gap and the current in said voice coil.

4. A loud speaker including in combination a ferro-magnetic field structure having an air gap, an exciting coil for magnetizing said field structure, a sound reproducing diaphragm, a short circuited voice coil supported by said diaphragm and situated in said air gap, said voice coil being composed of material having a high thermal coefficient of resistivity, said exciting coil being energized by a current having an alternating component superimposed a direct component, said voice coil having an alternating current induced therein functional of the alternating component of the exciting current, and said voice coil being mounted so as to vibrate in said air gap due to the interaction of the flux in said air gap and the current in said voice coil.

5. An electro-acoustic transducer comprising a field structure having an air gap, means for producing a magnetic field across said air gap, a diaphragm, a voice coil mechanically connected to said diaphragm and disposed in said air gap, said voice coil being composed of material having a high thermal coefficient of resistivity.

6. In combination with an electronic amplifier of the type producing an output current containing a direct current component and an alternating signal current, a loud speaker including a ferro-magnetic field structure having an air gap, an exciting coil for magnetizing said field structure, and a short-circuited voice coil situated in said air gap, said exciting coil being energized by the output current of said amplifier, said voice coil having an alternating current induced therein functional of the alternating component of said output current and said voice coil being mounted so as to vibrate in said air gap due to the interaction of the flux in said air gap and the current in said voice coil.

7. In combination with an electronic amplifier of the type producing an output current containing a direct current component and an alternating signal current component, a sound reproducer comprising a field coil connected in the output circuit of the amplifier, a sound reproducing diaphragm, a conductive member mechanically connected to said diaphragm and disposed in the magnetic field created by said coil,

whereby a current proportional to said signal current is induced in said conductive member and said induced current flowing in said conductive member disposed in the said field created by the 5 direct current component of said output current causes said member to move in directions and with forces depending upon the direction and intensity of said signal current.

8. A loud speaker comprising a field structure 10 having an air gap, means associated with said field structure for producing a magnetic field across said air gap having a direct current component and having a component varying in accordance with a sound to be reproduced, a short 15 circuited voice coil positioned in said field whereby voice currents corresponding to said varying component of said field are induced therein and the presence of such voice currents causes said voice coil to vibrate in accordance with the direction and magnitude thereof, and means for translating said vibrations into sound.

9. In combination with an electronic amplifier, a sound reproducer comprising a field coil connected in the output circuit of the amplifier, a 25 sound reproducing diaphragm, a conductive metallic plate mechanically connected to said diaphragm and disposed in the magnetic field created by said coil, whereby eddy currents proportional to said signal currents are induced in said 30 conductive member, and said member moves in directions and with forces depending upon the direction and intensity of said signal current.

10. In combination, an impedance coupled electronic amplifier and a loud speaker, said loud 35 speaker having a field structure and a voice current carrying member disposed in the field thereof, said field comprising a direct current component and an alternating current signal component, said field being produced in part by a 40 coil energized by the output of said amplifier and in part by a coil wound on said field structure and constituting a coupling impedance for said amplifier.

11. In combination with an impedance coupled 45 amplifier, a sound reproducer comprising a field structure, an exciting coil therefor connected in the output circuit of the amplifier, another exciting coil therefor constituting a coupling impedance for said amplifier, a sound reproducing 50 diaphragm, a closed circuit conductive member mechanically connected to said diaphragm and disposed in the magnetic field created by said coil, whereby a current proportional to said output current is induced in said conductive member, and said member moves in directions and with forces depending upon the direction and intensity of said output current.

JOHN J. MOYNIHAN.
